UNITED STATES PATENT OFFICE

JOSEPH A. ANGLADA, OF JENKINTOWN, PENNSYLVANIA

SLEEVE VALVE INTERNAL COMBUSTION ENGINE

Application filed February 12, 1927. Serial No. 167,617.

This invention relates to an improvement in rotary sleeve valve internal combustion engines.

It is an object of this invention to provide 5 a rotary sleeve valve internal combustion engine with an inner working cylinder insertable from below and having an integral artificially cooled upper combustion portion.

Another object of this invention is to provide 10 simple means for maintaining the inner working cylinder in alignment within the outer cylinder.

A further object of this invention is to provide 15 a rotary sleeve valve internal combustion engine having a stationary inner working cylinder supported against axial movement at its lower end and having an integral artificially cooled head forming a combustion chamber and acting to cool the valve sleeve 20 on the inside thereof.

Another object of this invention is to provide 25 a rotary sleeve valve internal combustion engine with an inner working cylinder having an integral head, and being removable from below without disturbing the sleeve 30 valve or the main engine head.

Another object of this invention is to simplify 35 the construction and assembly of a rotary sleeve valve internal combustion engine and increase the efficiency thereof.

Various other objects and advantages will appear as the description proceeds.

Referring now to the drawing which discloses 40 a preferred form of embodiment of my invention:

Figure 1 is a sectional view of a single cylinder engine showing my invention applied thereto.

As shown in the figure the engine consists 45 of the usual counterbalanced crankshaft 1, connecting rod 2, and piston 3. The crankshaft is mounted in bearings 4, preferably of the split type, in the crank case 5.

Extending upwardly from the crank case is 50 a jacketed cylinder 6 which may be either

integral with or detachably connected to the crank case in any desirable manner. Concentric with, and spaced from the cylinder 6 is an inner working cylinder 7 mounted at its lower end by a shouldered flange 8 and bolts 9. 50 The piston 3 reciprocates in this working cylinder 7.

A rotating sleeve valve 10 is located in the space between the two cylinders and is driven from the crank shaft either continuously, intermittently or at a variable speed by any suitable means as through gears 11, stub shaft 12, bevel gear 13, and gear 14 on the sleeve valve 10, as is clearly shown in the drawing.

The upper end of the working cylinder 7 60 is closed by a ported water jacketed combustion chamber formed integral with said working cylinder. This water jacket, designated as 15 on the drawing, is designed not only to cool the combustion chamber and ports, designated as 16 and 17, but also to cool the upper portion of the sleeve valve 10. The water jacket being integral with the working cylinder materially cools the side walls thereof, and substantially eliminates the troublesome 65 expansion problem thus permitting a very simple and efficient construction. Extending upwardly from the outer closed end of the working cylinder 7 and in axial alignment therewith, is a short cylindrical threaded portion 18, the function of which will be fully described hereinafter.

The jacketed outer cylinder 6 is provided with ports which align with the ports in the inner working cylinder 7. The sleeve valve 80 10 is also provided with one or more ports which, as the sleeve valve rotates, come into alignment with the ports in the cylinders 6 and 7 thus opening and closing these passageways. The number of ports in the sleeve valve 85 is, of course, determined by the relative speed of rotation of the sleeve valve and the crank shaft. In a four cycle engine each port must be opened once every two revolutions of the crank shaft.

The upper end of the inner working cylinder 7 is held in centered position with respect to the outer cylinder 6 by a main cylinder head 19 which is provided with a central opening 20. This head 19 is secured by bolts 21 to the outer cylinder 6 with the central opening 20 concentric with said cylinder 6. The cylindrical threaded portion 18 of the inner working cylinder 7 projects through the central opening 20 in the main engine head 19, and is clamped thereto by nut 22, thus centering the cylinder 7 within the cylinder 6.

The main engine head 19 is provided with cooling medium circulating passages 23 which communicate with the jacket of the cylinder 6 and the water jacket 15 of the inner working cylinder 7 as is clearly shown in the drawing. It is, of course, understood that while not shown in the drawing suitable gaskets will be provided between the main engine head 19 and the cylinders 6 and 7.

Antifriction thrust bearings 24 and 25 are provided at the ends of the rotary sleeve valve 10. The upper bearing 24 also serves to help center the upper end on the working cylinder 7. If desired, these bearings may be mounted in retainers of which there are many types now in common use. An annular groove 26 is provided in the flange 8 of the inner working cylinder 7 to receive the lower thrust bearing 25.

A lubrication chamber 27 surrounds the lower end of the rotary sleeve valve 10. This chamber contains not only the driving gears 13 and 14 for the said valve 10, but also the thrust bearing 25 and provides perfect lubrication and protection for these parts as well as lubrication for the valve.

The inner working cylinder 7 is of uniform diameter from the flange 8 at its lower end to the main engine head 19. This feature not only reduces the manufacturing and assembling costs, but permits the inner working cylinder to be withdrawn from below without disturbing the sleeve valve 10 or the main engine head 19. After withdrawing the inner cylinder 7, the sleeve valve 10 may also be withdrawn from below by first removing the driving gear 13 and its stub shaft 12.

Various changes in the construction of the embodiment illustrated in the drawing may be made without departing from the spirit of the invention, and I do not, therefore, desire to limit myself to the specific construction shown and described, but to interpret the invention broadly within the scope of the appended claims.

What I claim as my invention is:

1. In an internal combustion engine of the rotary sleeve valve type an outer cylinder, an inner stationary working cylinder insertable from below and having a water cooled combustion chamber formed integral with and

closing its upper end, and extending adjacent said sleeve valve.

2. A rotary sleeve valve internal combustion engine, having an outer water cooled cylinder, a stationary inner working cylinder spaced from said outer cylinder, and a sleeve valve rotating in the space between said cylinders, said stationary inner working cylinder being insertable in the outer cylinder from below, means to align said inner cylinder at the top thereof, means to align and secure the inner cylinder against axial movement at the bottom thereof including cooperating flanges on the inner and outer cylinder and a water jacketed combustion chamber closing the top of the inner cylinder and formed integral therewith, and surrounding the intake and exhaust ports in said cylinders.

3. A rotary sleeve valve internal combustion engine having an outer water cooled cylinder, a stationary inner working cylinder spaced from the outer cylinder and insertable from the bottom, a sleeve valve rotating in the space between said cylinders, a water cooled combustion chamber formed integral with the inner cylinder, a detachable main engine head having water passages therein communicating with the water jacket of the outer cylinder and the water jacket of the combustion chamber.

4. A rotary sleeve valve internal combustion engine having an outer water cooled cylinder, a removable water cooled cylinder head, a stationary inner working cylinder spaced from the outer cylinder and centered at the top by said cylinder head, a sleeve valve rotating in the space between said cylinders, said inner cylinder being stationarily mounted by a flange at its lower end and having its upper end closed by a combustion chamber formed integral therewith, the inner cylinder having a substantially uniform external diameter from the flange at its lower end to the top of the combustion chamber closing its upper end, and a lubrication chamber surrounding the lower portion of the sleeve valve closed by the flange on the inner cylinder.

5. In a rotary sleeve valve internal combustion engine, an outer cylinder, an inner cylinder spaced from the outer cylinder, a sleeve valve rotating in the space between said cylinders, a lubrication chamber surrounding the lower portion of the rotary sleeve valve and containing driving gears, and antifriction bearings for the top and bottom of the sleeve valve, the lower side of the lubrication chamber being closed by a flange on the inner cylinder, the upper part of the lubrication chamber being adjacent the water jacket and cooled thereby.

6. A rotary sleeve valve internal combustion engine having an outer water cooled cylinder, a stationary inner working cylinder spaced from said outer cylinder, a sleeve valve

rotating in the space between said cylinders and a detachable water jacketed cylinder head, said stationary inner working cylinder being fixed at its lower end and having its upper end closed by a water cooled combustion chamber formed integral with said stationary inner working cylinder and secured to said head, said chamber cooling said sleeve valve.

10 In testimony whereof I have affixed my signature to this specification.

JOSEPH A. ANGLADA.
